DESIGN FOR A PELLET

Edgar T. Meakin, San Francisco, Calif.

Application April 17, 1935, Serial No. 56,433

Term of patent 7 years

To all whom it may concern:

Be it known, that I, Edgar T. Meakin, a citizen of the United States of America and a resident of the city and county of San Francisco, State of California, have invented a new, original, and ornamental Design for a Pellet, of which the following is a specification, reference being had to the accompanying drawing forming a part hereof.

Figure 1 is an end elevation of a pellet showing my new design.

Figure 2 is a side elevation of such pellet.

I claim:

The ornamental design for a pellet, substantially as shown.

In testimony whereof, I have hereunto set my hand.

EDGAR T. MEAKIN.
